PORTABLE MIXING TANK

Frederick L. Craddeck, Rochester, N. Y., assignor
to Mixing Equipment Company Inc., Rochester, N. Y., a corporation of New York

Application August 15, 1935, Serial No. 36,422
Renewed November 3, 1936

16 Claims. (Cl. 259—109)

This invention pertains to mixing tanks designed to be used in combination with agitators and associated devices.

One object of this invention is to provide improved devices of this general nature and consists in the improvement, design, arrangement and/or combination of one or more of contributing factors. An embodiment of my invention will be described in the following detail description.

Another object of my invention is to provide an improved method of mixing. Specific objects of my invention are to provide improved devices and methods particularly suited to the mixing of paint materials and other sluggish viscous mixes.

Referring to the accompanying drawings.

Fig. 1 is a plan view of an improved mixing tank combined with a mixer.

Fig. 2 is a side elevation of the device of Fig. 1.

Fig. 3 is a section of Fig. 2 taken on the line 3—3.

Fig. 4 is an enlarged fragmentary section of the loose manhole cover of Fig. 1 taken on the line 4—4 thereof.

Fig. 5 is a fragment of the device of Fig. 1 taken on the line 5—5 thereof.

Fig. 6 is an enlarged fragment of the device of Fig. 3 taken on the line 6—6 thereof.

Fig. 7 is a view on a reduced scale of the device of Fig. 2 supported free of the floor on a lift truck.

Fig. 8 is a view corresponding to Fig. 3 of a modification and

Fig. 9 is a view corresponding to Fig. 6 taken on the line 9—9.

The numeral 1 indicates a sheet iron paint mixing tank which is provided with four legs 2, widely spaced to support the tank stably on a floor, made of pipe and secured to the tank 1 by means of brackets including lower flanges, preferably of triangular shape, and upper flanges and webs, as indicated. A dished bottom 3 having an upwardly projecting motor housing 4, and a removable cover 5 are also provided for the tank 1.

The housing 4 encloses a gear head motor 6, mounted on a motor mounting plate 7 which is welded to the tank 1. Thus the motor 6 does not project beyond the adjacent leg 2. It is of importance that the motor 6 avoid projecting beyond the adjacent leg 2 to eliminate danger of it being damaged by striking obstructions as the tank 1 is transported from one part of a paint factory to another.

The cover 5 of tank 1 is provided with a man-

hole 8, having a loose manhole cover 9, and a square hole 10 is also formed in cover 5, through which the tank 1 may be filled. The bottom 3 is strengthened by means of a reinforcing plate 12, provided with a tapped hole 11 which is designed to receive an openable closure means to empty the tank at the will of an operator.

A valve 40 for this purpose is shown in Fig. 2, with an extension handle 41, conveniently located outside the tank.

The motor housing 4 permits the propeller agitator 14 to be mounted low in the tank. It also positions the agitator so that the propeller stream only has a short distance to flow before striking the opposite side of the tank. This promotes rapid and thorough mixing.

In Figs. 3 and 6 a propeller agitator 14 is indicated as mounted on shaft 15 which is journaled in a stuffing box and bearing assembly 16. The right hand end of the shaft 15 is provided with a flexible coupling 17 which is driven from the gear head motor 6. The centre axis of shaft 15 is parallel with a diameter of tank 1 and spaced from the vertical axis of the tank 1 a distance equivalent to the radius of propeller agitator 14. This off center positioning of shaft 15 causes a slow rotation of the mix in the tank in addition to the movement thereof in the general direction of the propeller stream. The actual mixing occurs at the member 14 and in the propeller stream which it creates while the slow rotation causes all parts of the mix in tank 1 to be successively acted upon.

In Figs. 3 and 6 arrows indicate the general direction of the flow of the mix and also show how the stream of mix from propeller agitator 14 is made tortuous by bending around the motor housing 4. This tortuous flow of the mix around the motor housing 4, tends to facilitate intimate mixing of paint materials and the flexing of the stream, as shown by the arrows, is very effective. An improved method of mixing results from this arrangement of the bulkhead or motor housing 4 as the heavy particles resting on the bottom are, with its aid, effectively dispersed throughout the mix by member 14.

In Fig. 7 a lift truck 17 is shown resting on a floor 18. Truck 17 is provided with a platform 19 which is shown in its up position supporting tank 1. When platform 19 is lowered the legs 2 of tank 1 rest on floor 18 and truck 17 can be withdrawn for use elsewhere until tank 1 is to be again moved from one paint mill to another or elsewhere in the factory.

It will be noted that the space beneath tank 55

1, between legs 2 is unobstructed so that truck 17 fits under tank 1, between any pair of its legs 2, which facilitates the transportability of tank

1. The lower edge of tank 1 is formed like a skirt, provided with a reinforcing ring 20 welded to it, as shown in Fig. 6, so as to make tank 1 strong and rugged enough to be safely picked up and lowered on platform 19 without damage. Thus the bottom of the skirt acts as a foundation, for tank 1, on platform 19.

It will be noted in the modification of Figs. 8 and 9 that the propeller 140 has the axis of its shaft 150 intersecting the vertical centre axis of the tank 101 instead of being in the off centre position shown in the preferred construction of tank 1 in Fig. 3. This tends to make both sides symmetrical and thus facilitate fabrication of the tank 101 of Figs. 8 and 9. However, in order that a slow rotation about the vertical centre axis of the mix in tank 101 may be produced and all parts of the mix successively acted upon and mixed by propeller 140 as they are by propeller agitator 14 in tank 1, some auxiliary means is required. The rudder 210 which is merely a bent plate welded to bottom 300, of tank 101 is such an auxiliary means. It deflects the lower portion of the propeller stream of the mix as indicated by the arrow near member 300. Rudder 210 thus causes a slow rotation of the mix in tank 101 approximating the slow rotation of the mix in tank 1.

The rudder 210 causes the mix to rotate slowly around a substantially vertical central axis of tank 101 in a counterclockwise direction. This is opposite to the corresponding slow rotation of the mix in tank 1. However, the rudder 210 can be reversed in curvature and placed on the other side of shaft 150 if clockwise slow rotation of the mix in tank 101 is desired.

40 By making the inside of the tank's wall unsymmetrical or irregular so that the propeller stream will be deflected to one side of the vertical axis or by distorting the motor housing an equivalent rotation of the mix can be effected. 45 All these alternative arrangements can be made to produce this same sort of slow rotation of the mix.

The off centre housing 4 of Fig. 3 tends to produce such an effect which is, however, somewhat masked by the more conspicuous effect resulting from the off centre axis of agitator 14.

Valve 141 in Fig. 9 discharges tank 101 at the will of the operator.

In modern paint making artificial materials 55 like, for instance Bakelite resins and oils, are much used and occasionally the pigment, after having been ground in oil to a thick pasty consistency, polymerizes prematurely. This turns the material into a sort of jelly and tends to spoil it for paint. However, if the polymerization is noticed when it starts it can often be arrested by violently mixing the thick pasty material with thinners to the consistency of the ready 60 mixed paint of commerce.

65 For such contingencies I provide the motor 66 with a normal speed suited to usual requirements and a special high speed about a third or a half faster. A control switch 401 having an off position contact 402, a normal position contact 403 and a high speed contact 404 controls motor 66, for these requirements.

I do not limit myself to the exact construction shown for modifications of this invention 70 may be made in accordance with the progress

of the art without departing from the spirit hereof.

I claim:

1. A mixing tank provided with a motor housing extending into and forming a part of the tank whereby a motor may be accommodated without substantial projection outside the tank, a motor therein and a substantially horizontal agitator shaft revolvably mounted at the inner end of the housing, provided with an agitator 10 at its inner end and connected to the motor at its outer end.

2. A mixing tank provided with and including a motor housing, substantially below the normal level of a mix, forming a portion of the bottom 15 of the tank, of such a shape as to baffle and cause a propeller stream to take a tortuous course, a propeller agitator means at the inner end of the housing, within the tank, designed to create a propeller agitator stream in the mix and to mix 20 same; the inner end of said housing and said agitator means being adjacent the vertical centre axis of the tank.

3. A mixing tank provided with and including a motor housing substantially below the normal 25 level of a mix, forming a portion of the bottom of the tank, of such a shape as to baffle and cause a propeller stream to take a tortuous course, propeller agitator means at the inner end of the housing, so positioned as to tend to create a propeller stream substantially across the vertical 30 centre axis of the tank, means in the path of said stream to deflect at least a portion thereof horizontally, said stream then being deflected by the opposite wall, so as to flow upwardly and 35 slowly around the vertical centre axis of the tank, then into the propeller stream and repeat, whereby all parts of the mix tend to be acted upon by the agitator means at one time or another, during a mixing operation.

4. A portable mixing tank provided with a body, widely spaced legs therefor, whereby a truck may be run under the body and between the legs, level means at the edge of the bottom of the tank to provide secure seating on the truck, an agitator having a substantially horizontal shaft, near the bottom of the tank, a motor mounted at the tank in driving relation to the agitator and positioned substantially within a boundary line surrounding the tank and legs.

5. A mixing tank provided with a bottom pitched toward a discharge aperture so as to drain thereinto, having an upwardly projecting portion at one side forming a substantially horizontal motor housing, a skirt means provided with a substantially level lower portion at the edge of said bottom, and legs secured to the tank and projecting below said level portion.

6. A mixing tank provided with a bottom pitched toward a discharge aperture so as to drain 60 thereinto, having an upwardly projecting portion at one side forming a substantially horizontal motor housing, a hole in the tank side wall whereby a motor may be inserted into the housing, a skirt means provided with a substantially 65 level lower portion at the edge of said bottom, and legs secured to the tank and projecting below said level portion.

7. A mixing tank provided with a bottom pitched toward a discharge aperture so as to drain 70 thereinto, having an upwardly projecting portion at one side forming a substantially horizontal motor housing, an aperture at the outer end thereof and a floor means in the housing whereby a motor may be mounted, a skirt means pro- 75

vided with a substantially level lower portion at the edge of said bottom, and legs secured to the tank and projecting below said level portion.

8. A mixing tank provided with a bottom pitched toward a discharge aperture so as to drain thereinto, having an upwardly projecting portion at one side forming a substantially horizontal motor housing, a skirt means provided with a substantially level lower portion at the edge of said bottom, and legs; said tank being substantially in the form of a vertical cylinder and said legs being secured to the tank and positioned so that said legs are fixed substantially outside the circumference of the tank, all of said legs projecting below said level portion.

9. A mixing tank provided with a motor housing extending into and forming a part of the tank, having a narrow upper portion and widening out at its lower portion where it merges with the tank bottom, whereby a motor may be accommodated without substantial projection outside the tank, a motor therein and a substantially horizontal agitator shaft revolvably mounted at the inner end of the housing, provided with an agitator at its inner end and connected to the motor at its outer end.

10. A portable mixing tank including a dished bottom surrounded by a curved side wall, said wall extending downwardly at a skirt portion, brackets including triangular flanges attached at their sides at said skirt portion, projecting outwardly from same, webs associated with said flanges and downwardly projecting legs at the outer portions of said brackets.

35 11. A portable mixing tank having a curved side wall and dished bottom, said side wall being provided with a skirt portion having a level lower edge whereby the tank may be supported on a lift truck, brackets projecting outwardly from said skirt portion and widely spaced legs projecting downwardly from the outer ends of said brackets, whereby the tank may be supported on a floor and straddle a lift truck.

12. A portable mixing tank including a dished bottom surrounded by a curved side wall, said wall extending downwardly at a skirt portion, brackets including triangular flanges attached at their sides to said skirt portion, projecting outwardly from same, webs associated with said

flanges and downwardly projecting legs at the outer portions of said brackets, adjacent legs being spaced apart a distance substantially equivalent to the width of the tank, whereby a lift truck may be accommodated.

13. A portable mixing tank having a curved side wall and dished bottom, said side wall being provided with a skirt portion having a level lower edge, whereby the tank may be stably supported on a lift truck, brackets projecting outwardly 10 from the skirt portion and widely spaced legs projecting downwardly from the outer ends of said brackets, whereby the tank may be supported on a floor and straddle a lift truck, adjacent legs being spaced apart a distance substantially equivalent to the width of said tank.

14. The combination of a mixing tank provided with a wall having an internal protrusion, an agitator shaft revolvably mounted in and through a wall of said protrusion, an agitator at the inner 20 end of said shaft, a gear means at the outer end thereof and a motor mounted independently of said shaft and attached to said tank at the outer and lower portion of said protrusion, below said shaft and in permanent driving relation to said 25 gear means.

15. A mixing tank provided with a motor housing extending into and forming a part of the tank, widely spread apart legs, attached to the tank, one of which is positioned substantially 30 below the outer end of said housing, whereby a motor may be guarded by such leg, a motor in said housing and a substantially horizontal agitator shaft revolvably mounted at the inner end of the housing, provided with an agitator at its 35 inner end and connected to the motor at its outer end.

16. The combination of a tank, a mixing propeller device therein, so positioned as to create a stream of mix across the tank and means for 40 modifying the flow of such a stream, said means including a stream deflector member within, and extending unsymmetrically at least partly across the tank, whereby mixing is promoted and said stream is guided so as to flow around a horizontal axis and slowly around a vertical central axis of the tank before again flowing through the mixing propeller device.

FREDERICK L. CRADDOCK.
